UNITED STATES PATENT OFFICE.

HAZOR J. SMITH, OF SPRINGFIELD, MASSACHUSETTS, ASSIGNOR, BY MESNE ASSIGNMENTS, OF ONE-FOURTH TO WILLARD REID, OF SPRINGFIELD, MASSACHUSETTS, ONE-FOURTH TO ALFRED BUCKLEY, JR., OF PROVIDENCE, RHODE ISLAND, AND ONE-FOURTH TO JOHN W. SCOTT, OF PHILADELPHIA, PENNSYLVANIA.

REFRIGERATOR SYSTEM

Application filed June 5, 1920, Serial No. 386,884. Renewed March 31, 1925.

To all whom it may concern:

Be it known that I, HAZOR J. SMITH, a citizen of the United States, residing at Springfield, in the county of Hampden and State of Massachusetts, have invented certain new and useful Improvements in Refrigerator Systems, of which the following is a specification.

This invention relates to a system of refrigeration of the type usually employed to cool an ice box in a private home although its use is in nowise limited thereto, and has for its object to produce a machine which will automatically complete its freezing work and at the same time be susceptible of control from the brine temperature.

My invention consists in the novel arrangement and combination of parts more fully pointed out hereinafter and particularly described in the appended claims.

In the drawing, which is to be taken merely illustrative of one manner of carrying out my invention.

The figure is a diagrammatic view of a cooling system constructed according to my invention.

The gas used in this system is ethyl chloride, which enters a compressor shown diagrammatically at A. Upon compression it passes in gaseous form to the condenser B assuming the liquid form, thence passing to the receiver at the end of the condenser shown at C. Passing through an expansion valve D of ordinary construction it enters the bottom of element E which is an ice freezing chamber. This member is composed of an outer shell 2 filled with insulating material 3 such as cork or its equivalent which surrounds a chamber 4 for the passage of the expanding ethyl chloride. Adjacent this gas chamber on the inside is a brine space 5 surrounding an ice can 6. This can is adapted to be filled with water and thus both a refrigerating action may be had to cool the household ice box and at the same time produce ice in any desired form for drinking water or other use.

Connected to member E in series and constructed to receive the expanding ethyl chloride from the top of said freezing chamber is a brine tank F and expander drum G.

This tank consists of a brine tank 7 enclosing within itself an annular gas chamber

G for the ethyl chloride. The brine tank F is provided with a central air passage 8. The ethyl chloride may or may not be completely gasified by the time it leaves the freezing chamber, but upon reaching the expander drum, complete evaporation takes place thereby absorbing its full capacity of heat and chilling the brine. This brine tank serves as a "cold" storage member to maintain a temperature equilibrium in the ice box. The air in the box is free to circulate on all sides and down the center passage of the tank and the large amount of exposed surface of the tank adds greatly to the efficiency of the machine.

Interposed in the system at the tail end of the frost line or at the point of greatest temperature variation, such as in the brine tank F, I provide a thermostatic control or bulb H connected to the driving motor, to regulate the stopping and starting thereof. When the machine is in operation and the temperature of the ethyl chloride or brine around it drops below the point at which control H is set, the motor will be automatically cut off, that is, when once started in the normal manner, the machine will continue to run until the temperature at the thermostatic bulb reaches the point at which it is set to cut out. When the temperature of tank F rises above the setting of thermal control H, the motor is started and the operation continues.

Before entering the compressor A the gas passes through a check valve of ordinary construction J which prevents the reverse flow of the sealing medium while the machine is idle. When the machine stops running the check valve is closed, as will be readily understood, due to the difference in pressure of the high and low sides.

By this arrangement of parts, it is possible to clean either the expander drum in the brine tank or the ice tank assembly by merely breaking the line on the low pressure side of the expansion valve D. The resulting evaporation of the ethyl chloride reverses the normal flow of the same and cleans out that part of the system between the two valves D and J. This is highly important from a service standpoint.

Outside of any mechanical device used, I have applied certain scientific laws that are

highly valuable in practice which comprise certain balances established in this invention.

Any modification of the balances will lengthen or shorten the running time and the time given to freezing. The surface of the freezer and the differential established between the freezing water and the refrigerating agent will determine how much heat will pass and these characteristics necessarily determine the degree of effect which the imposition of the freezer will have on the normal expansion lines. A machine of a total fixed capacity will chill a given body of brine to a certain temperature in a given time. Now superimpose another body of water to be chilled and frozen. Allow this body to furnish heat to the refrigerant before it enters expansion coil in the brine tank. Part of the total capacity of the machine is being absorbed by this superimposed load. The excess passes on to the brine tank. I have established a ratio, or balance, between these two elements—viz, the brine tank and the freezer, so that when the machine starts to run it will continue to run, if there is any superimposed load in freezer, until freezer load is removed by having the water frozen and no longer giving up heat. Any change in the balance established in this process will change the relative running periods.

If the balance is incorrect the machine will reduce the temperature of the brine to the cut-out point before the water is frozen. The machine then would stop running and leave the water partly frozen.

The fact that the capacity of the compressor varies nearly directly with the vacuum of the low side in ethyl chloride machines gives me a means whereby I can alter the major capacity factor to bring the absorption capacity of the low side elements up to it and therefore strike a balance, or rather bring the capacity of the compressor down to the maximum heat absorption capacity of the low side when the freezer is not in use, and then the surface of the freezing water exposed to the cooling of the evaporating agent will produce a factor of transfer that can be readily balanced with the brine surfaces to determine the elapsed time of freezing.

The capacity factor of the compressor can be altered by adjusting the evaporating tension of the low side which alters the volumetric capacity of the compressor. Any altering of the back pressure of the low side will alter the evaporating tension of the low side.

As a matter of illustration, let the compressor A have a thermal factor of 1,000 B. t. u. per hour, let the ice box take on 500 B. t. u. per hour, let the brine body have sufficient weight so that its total specific heat through the 5° F. range of the ther-

mostat G shall be 500 B. t. u.; now if the compressor starts, it will in one hour take 500 B. t. u. from the ice box and 500 B. t. u. from the brine and reduce the temperature of the brine 5 degrees to where the thermostat cuts out. It will stand idle until the brine has taken on 500 B. t. u. from the ice box and its temperature raised by this heat to where the thermostat cuts in and starts the motor. Now place 3 pounds of water at 56 degrees Fahr. in the freezer E. This water will require the extraction of 500 B. t. u. to freeze it. The can and cell have surface enough to permit the passage of 250 B. t. u. per hour from the water to the refrigerating agent within the wall of the cell. The relationship of the various heat factors reduced to time are as follows:

The compressor can handle 1,000 B. t. u. per hour. The freezer supplies 250 B. t. u., the ice box gives the brine 500 B. t. u., which is 750 B. t. u. or 250 B. t. u. less than the capacity of the compressor. Now the excess capacity of the compressor is used to cool the brine and reduce its temperature and in the hour we have an excess factor of 250 B. t. u. which will reduce the brine body 2½° F. and in order to bring the brine to the cut out point of 5° F. lower than the cut in, we must run two hours and in that two hours we have frozen the water by extracting its 500 B. t. u.

The balance is established between the compressor and the rest of the cycle by giving the brine tank absorption capacity and weight sufficient to establish any running proportion desired. It may run only one third of the time if the box takes on one third of the capacity of the compressor. Whatever ratio of run to stand is found the transfer capacity of the freezer must be such as to modify the total heat given to the compressor to the extent of supplying enough heat to prevent the compressor gaining on the brine faster than the predetermined freezing period. The setting of the expansion valve is a very material factor in not only reducing the capacity of the compressor or increasing it as the case may be but also in the concentrating of the refrigerative effort nearer the head of the expansion lines or extending that effort farther along the lines. Heat will be absorbed directly proportionate to the differential established and therefore, a higher tension will lengthen the differential in the freezer and shorten the lines of evaporation in the brine cooler, thus materially changing the balances between the two elements.

The back pressure determines the capacity of the compressor. The expansion valve determines the back pressure. By adjusting the expansion valve the capacity of the compressor is changed to balance any cycle as will be readily understood.

What is claimed is:

1. In a household refrigerating machine of the type described, the combination of a compressor, a condenser, an automatic expansion valve, a brine tank, a brine cooling expansion drum within said tank, a freezing container interposed in the expansion line behind the expansion valve and ahead of the expansion drum, and means for

controlling the operation of the compressor 10 by the temperature of the brine tank regardless of whether the freezing container is in use or not.

2. A device as recited in claim 1 in which the expansion valve may be set to vary the 15 capacity of the compressor.

In testimony whereof I affix my signature.

HAZOR J. SMITH.
